UNITED STATES PATENT OFFICE.

ADOLPH HUBER, OF ST. LOUIS, MISSOURI

ELEVATOR DROP BAR.

Application filed March 2, 1925. Serial No. 12,673.

My invention relates to improvements in drop-bars for elevators, the same being a bar placed across the opening to the elevator shaft, for preventing injury to one stepping into the shaft in the dark, and for other reasons. These bars may be either vertically slideable to permit the elevator to be loaded or unloaded or may be pivoted at one end so as to permit the same to be swung upwardly out of the way. My improvement relates to the last-mentioned type of drop-bar.

My invention has for its objects the provision of a bar of the character described, which may be manually moved to open position when desired for unloading or loading the elevator at the floor level, and will be automatically actuated to closed position by the movement of the elevator in either direction past the floor level.

Other objects of my invention are the provision of a plurality of independent means, operable during the closing movement of the bar, to retard and cushion said closing movement in a predetermined manner and to reduce shock, wear and noise.

The invention has among its other objects the provision of a drop-bar of the character described, which shall be simple in operation and construction, convenient, economical, reliable, and efficient and satisfactory for use wherever found applicable.

Many other objects and advantages of the construction herein shown and described will be obvious to those skilled in the art to which this invention appertains, from the disclosures herein given.

In the drawings, wherein like reference characters indicate like or corresponding parts throughout the views,

Figure I is a vertical elevation of my device, with the drop-bar in closed position;

Figure II is an end elevation of the same, showing the bar in section, and the trip lever adjacent the tripping members of the elevator cage;

Figure III is a vertical elevation of the parts shown in Figure I, except that the drop-bar is in its open or raised position;

Figure IV is an end elevation of the parts shown in Figure II; and

Figure V is an end elevation of the frictional speed retarding means engageable with the free end of the drop-bar.

In the drawings, wherein I have illus-

trated the preferred embodiment of my invention 11 indicates the drop-bar adapted to be normally in closed or horizontal position across the opening to the elevator shaft, said bar extending horizontally between the parallel vertical walls or uprights 26 and 29 at the forward sides of the elevator opening at the floor level. One end of the bar is pivoted to an upright post 18 adjacent the upright 29, by means of the pin 19, and has a pair of plates 12 fixed on either side thereof to form a reinforcement for said bar. A pair of plates 13 are arranged on either side of the upright 18 to provide a journal bearing for said pin 19. The other end of the drop-bar, the same being the free end, is adapted to be locked in place at the bottom of a vertically extending slot 32 provided in the upright 26, as shown in Figure V.

A spring-bar 25 is arranged to form one of the vertical walls of the slot, the same being fastened only at the upper end with the lower end free. This spring-bar extends in such a direction that it is inclined with respect to the cooperating side of the groove so as to make this groove or slot tapered or convergent toward its lower end, as shown. The lower or free end of the spring-bar is notched or shouldered as at 33 to engage over the top edge of the drop-bar when the latter is at its furthermost or final closed position, locking the same in place thereat in the bottom of the slot and wedging said drop-bar in the slot.

A handle or lever 24 is provided to engage the free end of the spring-bar 25 in order to release the free end of the drop-bar and permit the same to be manually lifted or swung to its open position when desired. A movement of the handle 24 will move the free end of the spring-bar to enlarge the slot sufficiently to lift the drop-bar past the notch or shoulder of the spring-bar.

A link 10 is pivoted at one end to the pivoted end of the drop-bar, the other end of the link being pivotally connected to the lower end of a vertically slideable rod 7, the latter passing through a pair of vertically spaced guides 6 and 9. The spacing between the guides is sufficient that the rod will always engage both of the guides during all of the movement thereof. A coiled spring 8 encircles the rod 7, the lower end of said spring resting against a washer

30 fastened on the rod by means of a cotter 31 movable to various adjustable positions longitudinally thereof through one of a series of openings 31'. The upper end 5 of said spring bears against the guide 6.

A strip of metal having a double-beveled cam 34 thereon extending at right angles thereto is indicated at 1, said member being vertically slidable in a pair of vertically 10 spaced guides 5-5. The guide 6, hereinbefore mentioned, is carried by the member 1 at its lower end, as shown.

A trip lever 2 is pivoted at one end to some stationary part of the door structure, 15 as the part 29, and extends through the cam 34 on the member 1, as shown, the free end of the lever projecting into the elevator shaft or opening for a purpose to be described shortly. A roller 2' is preferably 20 journaled in the free end of the lever. A plate 4 is preferably arranged spaced from the cooperating surface of the member 1 and fixed thereto to provide a guide and retainer for the lever where it passes 25 through said member. Two hardened pins or rollers 3 may be fixed, one at either side of the lever, between the plate 5 and the cooperating surface of the member 1, as shown.

30 A pair of double beveled cam members 22-22 are mounted upon one of the forward uprights 27 of the elevator cage, moving therewith in the path of the trip lever, and tripping the latter whenever the free end 35 of the lever projects into the path of movement of the members 22-22 fixed to the elevator.

As the free end of the drop-bar is released from its wedged latching position at the 40 bottom of the slot, and swung upwardly to open position against the vertical wall of the doorway leading to the elevator shaft, such movement will first lift the rod 7 upwardly until the spring 8 begins to compress, the latter then transmitting the movement to the slidable member 1, the latter actuating the trip lever to substantially horizontal position with the free end of the same extending into the path of vertical travel 45 of the members 22-22. In order to maintain the bar in its open position, a latching device is arranged at the free end of the bar, said latch being indicated by the numeral 23', and adapted to cooperate with 50 the other mating part 23 attached to a fixed structure, as the upright 29.

As the elevator moves away vertically 60 from its stopped position at floor level, one of the members 22, depending upon which direction the elevator is traveling, trips the lever 2, moving the latter and the member 1 therewith in one direction or the other, to cause the cam 34 carried by said slidable member to slide against the roller 21 mounted intermediate the ends of the drop-bar

and press the drop-bar out of its latched engagement with the latch 23. A spring 28 is arranged adjacent the pivoted end of the drop-bar, the same being placed under pressure by the drop-bar when opening the same, 70 and exerting its pressure to shove the drop-bar slightly, as soon as the bar has been tripped and released from the engagement at the latch 23.

The necessary upward or downward 75 movement of the slidable member 1 when releasing the latch 23 does not cause a corresponding movement of the rod 7, inasmuch as there is sufficient longitudinal play or yield therebetween, as shown.

It is apparent that unless some means were provided to take up the shock of the free fall of the drop-bar, said bar would make an undue amount of noise and quickly 80 wear out and shatter to pieces. There is a link 14 pivoted at one end to the hinged end of the drop-bar at the under side thereof, the lower end of the link being pivotally connected to the upper end of a vertically 85 slidable rod 15. Guides 20-20 are arranged on the post 18, adjacent the ends of the rod, and a coil spring 16 encircles the rod between the guides, one end of the spring being free and the other end bearing against an adjustably fixed washer or key 17 or the 90 like, the latter being insertable through one of a series of holes 17'.

The spring 16 will therefore act as a shock absorber and retard the speed of falling of 100 the drop-bar in the well-known manner, the spring expanding or elongating when the drop-bar is opened and being compressed when the bar is dropped. By adjusting the washers of the springs 8 and 16 various 105 amounts of play and degrees of compression may be obtained, thus compensating for wear between the parts.

In addition to this shock-absorbing and speed-retarding means, the free end of the drop-bar is acted on by independent speed-retarding means, the same comprising the frictional wedging of the bar in the tapered guideway as the bar drops toward the bottom of the slot, the free end of the bar being 110 locked in normal closed position by the spring-bar at the end of movement of the drop-bar in the bottom of the slot.

The plurality of speed-retarding means 115 will act in sequence in the following way. During the first part of the fall, the spring 16 will do the retarding, and as soon as the bar enters the tapered slot the frictional or wedging action will occur, both of these independent means working in unison thence to the end of fall of the drop-bar.

From the foregoing description it will be 125 seen that I have provided a drop-bar which may be manually raised from its normally latched horizontal position, to open position, and as soon as the elevator moves away from 130

the floor level, the movement will cause the bar to fall with retarded movement to its normally latched, closed position. The shock of falling, the wear of the parts, and shattering will be reduced, and the noise will be greatly minimized.

All of the parts are made of strong and durable material, making a device which shall be neat and attractive in appearance, and will last for a long period of time without attention other than an occasional oiling. All ropes, which deteriorate rapidly have been dispensed with, and hence the cost of upkeep is greatly reduced.

Having thus described my invention, it is obvious that various immaterial modifications may be made in the same without departing from the spirit of my invention; hence I do not wish to be limited to the exact form, construction, arrangement and combination of parts herein shown and described, except as limited by the claims.

What I claim as new and desire to secure by Letters Patent is:—

1. In a device of the kind described and in combination, an elevator drop-bar, mechanism adapted to be operated by the movement of the elevator to engage said bar in its open position to actuate said bar to its closed position, and means for frictionally retarding said closing movement of said bar.

2. In a device of the kind described and in combination, an elevator drop-bar, means operable by the elevator to release said drop-bar from its open position, and a plurality of means operable in sequence to resiliently and frictionally retard the falling movement of said bar to its closed position.

3. In a device of the kind described and in combination, an elevator drop-bar movable to open or closed position, means operable automatically by the elevator to release said bar from its open position, means independent of said first-mentioned means and cooperable with said bar after said release and actuating said bar toward its closed position, and means to retard the free fall of said bar to its closed position.

4. In a device of the kind described and in combination, an elevator drop-bar adapted to be manually raised to its open position, a latch holding said bar in its normally closed position, a second latch holding said bar in its open position, and a plurality of means cooperable with said bar to release it from engagement with said second-named latch to cause the bar to fall toward its closed position, and resiliently and frictionally retarding the fall of the bar to its closed, latched position.

5. In a device of the kind described and in combination, an elevator drop-bar hinged at one end and adapted to be swung to its open position and automatically held thereafter, mechanism operable by the movement

of the elevator for automatically dropping said bar to its closed position, and means for frictionally retarding the closing movement of said bar.

6. In a device of the kind described and in combination with an elevator, an elevator drop-bar adapted to be latched in open position, mechanism controlled by the movement of said elevator to release said latch, means resiliently pressing said bar toward its closed position, said means being operable after the release of said latch to cause movement of said bar, and means for controlling the fall of said bar in a predetermined manner.

7. In a device of the kind described and in combination with an elevator, a drop-bar adapted to be swung to its open position and latched thereat, means operable upon release of said latch to start said bar toward its closed position, and a plurality of means operable in sequence to yieldingly and frictionally retard the closing movement of said bar.

8. In a device of the kind described and in combination with an elevator, a pivoted drop-bar adapted to be manually moved to open position and held thereat, mechanism controlled by the movement of said elevator in either direction to release said bar, means operable when said bar is in open position for engaging with and pressing said bar toward closed position, and means for retarding the free fall of said bar.

9. In a device of the kind described and in combination with an elevator, a drop-bar adapted to be swung to substantially vertical open position, means for latching said bar in said position, means to release said latch, and means to yieldingly and frictionally retard the falling movement of said bar.

10. In a device of the kind described and in combination, an elevator drop-bar adapted to be manually raised to open position, a trip adapted to be set by said opening movement of said bar and operably connected to said bar with a yieldable connection therebetween, and a longitudinally yieldable member connected to said bar to resiliently counteract the closing movement thereof.

11. In a device of the kind described and in combination, an elevator drop-bar adapted to be manually raised to open position and latched thereat, and means adapted to be controlled by the movement of the elevator and cooperable with said bar to control the falling, closing movement thereof, said means comprising a cam engageable with said bar, a slid able member carrying said cam, a resiliently yieldable connection between said bar and member and transmitting movement therebetween, a trip lever engageable with said member to move said

cam to release said latch, said lever being in the path of movement of said elevator only when the bar is in its open position, means engaging with the bar in its raised position to shove the bar toward its closed position after the bar has been released from its latched open position, and means for retarding the closing movement of said bar.

12. In a device of the kind described and in combination, an elevator drop-bar pivoted at one end and adapted to be manually swung upwardly to open position, latch means engageable with the free end of said bar and adapted upon opening movement of the bar to hold said bar in open position, and means cooperable with said bar to initiate the downward swinging movement of the same to its closed position, said means comprising a cam engageable with

said bar intermediate its ends, a slidable member carrying said cam, a trip member engageable with said slidable member to actuate the latter, said trip being in the path of movement of said elevator only when the bar is in its raised open position, a resilient connection between said bar and slidable member and transmitting movement therebetween, a spring operatively engageable with the bar in its raised position to urge the same toward its closed position, a cushioning member connected to said bar to retard and cushion the fall of the same, and means frictionally engageable with the free end of said bar after a predetermined part of its fall, to retard the remainder of said fall in conjunction with the retarding by said cushioning member.

ADOLPH HUBER
